SHELL AND CAP FOR ELECTRIC LIGHT SOCKETS

Application filed June 26, 1925. Serial No. 39,637.

This invention relates to a metallic shell and cap for enclosing an electric light socket. It relates more particularly to a shell and cap of this sort, in which metal is struck out 5 from one of said members to permit these members to be telescoped one into the other and to prevent accidental withdrawal and also to prevent relative rotation between these members, while at the same time permitting the same to be easily manipulated for the purpose of separating the two members.

The invention will be understood from the description in connection with the accompanying drawings, in which Fig. 1 is a perspective view of the cap; Fig. 2 is a perspective view of the shell; Fig. 3 is an enlarged detail showing a portion of the shell; Fig. 4 is a section along the line 4—4 of Fig. 3 and 10 Fig. 5 is a section along the line 5—5 of Fig. 3. Fig. 6 is an enlarged view showing a modification.

In the drawings, reference character 10 indicates a metal cap for an electric light 25 socket shell which is provided with rectangular openings 11, made by cutting out the metal along the rim of the cap. The shell 12 is provided with the usual switch slot 13, which slot also permits the walls of the shell 30 to be sprung inwardly when desired. The shell 12 is provided near its upper end with projections that are made by slitting the shell horizontally or circumferentially along the line 14, and also slitting the shell along 35 the line 15 at an acute angle to the line 14, so that the end of the slits 14 and 15 terminate in a point, thus making a V-shaped notch or slit. The metal 16 of this V-shaped notch or slit is bent outwardly and the corner is then 40 bent inwardly to a radial line to form a shoulder 17 with a rounded edge 18, the walls of the metal constituting the shoulder 17 lying in a radial plane, which is parallel with and passes through the central axis of the shell. 45 The lower edge 19 of the metal 16 serves to prevent the shell and cap from being accidentally separated after they have been assembled, and the shoulder 17 prevents relative rotation between the cap and shell in one 50 direction. It will be noticed that the point

of the V-shaped metal 16 is bent inwardly to a radial line, as shown at 20 in Figs. 4 and 5, so that this point is flush with the inner wall of the shell 12, thus leaving an open space 21 between the wall 17 and the slit 15. A 55 similar slot and struck out metal is made at another portion of the shell 12 in the same horizontal plane, as indicated at 16', but with the shoulder 17' directed in the opposite direction so as to prevent relative rotation between the shell and cap in the other direction. Instead of having the two shoulders 17 and 17' 180 degrees apart, as indicated in Fig. 2, these shoulders may be made closer together and any convenient number of the 60 same may be provided. Instead of having the openings 11 in the cap and the projections 16 on the shell, these may be reversed, thus having the openings in the shell and the 65 projections extending inwardly on the cap. 70

In the modification shown in Fig. 6, instead of having the shell slit along horizontal lines, shown at 14 in other figures, the shell is slit along two lines 22 and 23 that are 75 approximately horizontal, but make an angle with each other, as shown at 24. The shell is also slit along the line 26, which line merges into the line 23 along the curved line 25 to leave a rounded corner. The shell is also slit along the line 27 which makes an angle 80 with the line 26. The tongue of metal is then bent outwardly and its edge is turned inwardly to form the wall 30, similar to the wall 17 in the other modification, this wall 85 30 having a rounded edge 31 that extends from the lower edge 28 of the extension 32 in a sloping direction to the wall of the shell itself. The rounded corner 29 which came out from the curved portion 25 rests on the outside of the shell against the 90 triangular portion 24, so that the tongue 32 will be prevented from being pushed inwardly when the shell is inserted into a cap.

The operation is as follows: When it is intended to insert the shell in the cap, it is 95 only necessary to press the two together, whereupon the sloping edges 18 (or 31) of the metal or projections 16 (or 32) operating as cams cause the shell to spring inwardly as these edges ride along the inner surface of 100

the cap, until the projections reach the holes 11, whereupon they will snap outwardly into position, the abrupt edges 19 (or 28) preventing separation of the members and the 5 radially disposed portions or walls 17 (or 30) preventing relative rotation between the cap and shell. It will be observed that no sharp corners will be exposed whereby the user might be injured, as the corner 20 (or 29) 10 is turned inwardly and the extreme projection of the edge 19 (or 28) will be very little, if any, greater than the thickness of the rim of the shell 11, so that this edge will not project much, if any, outside of the shell at any 15 point. There are no sharp edges or corners exposed upon which objects might catch.

I claim:

1. In an electric light fixture, a cap having openings therein, a shell slit along lines 20 at an acute angle to each other, the metal adjacent said slits being bent to form an extension to project into one of said openings when said cap is placed on said shell, the metal of said extension being bent backwards.
2. In an electric light fixture, a telescoping cap and shell, one of said members being provided with a circumferential series of openings and the other one being slit along 30 lines at an acute angle to each other and bent to form extensions to project into said openings when said cap and shell are assembled, the metal of said extension being bent backwards.
3. In an electric light fixture, a telescoping cap and shell, one of said members being provided with a circumferential series of openings and the other one being slit along lines at an acute angle to each other to form 40 extensions to project into said openings when said cap and shell are assembled, at least one of said lines being horizontal, and a portion of the wall of each of said extensions being at right angles to the surface of said member.
4. In an electric light fixture, a telescoping cap and shell, one of said members being provided with a circumferential series of openings and the other one being slit along lines at an acute angle to each other to form 50 extensions to project into said openings when said cap and shell are assembled, at least one of said lines being approximately horizontal, a portion of the wall of each of said extensions being at right angles to the surface of said member, and another portion of said wall lying in a plane at an acute angle to the axial direction of said member.
5. In an electric light fixture, a cap having openings therein, a shell slit along lines at an acute angle to each other, the metal adjacent said slits being bent to form an extension to project into one of said openings when said cap is placed on said shell, the corner of said extension resting against said shell.
6. In an electric light fixture, a telescoping

cap and shell, one of said members being provided with a circumferential series of openings and the other one being slit along lines at an acute angle to each other to form extensions to project into said openings when said cap and shell are assembled, the corners of said extensions resting against the side of said member.

7. In an electric light fixture, a cap having openings therein, a shell slit along lines at 75 an acute angle to each other, the metal adjacent said slits being bent to form an extension to project into one of said openings when said cap is placed on said shell, the corner of said extension resting against said shell and the 80 edge of said extension resting against the edge of an opening.
